HAIR FLUFFER

Martin Newman, 1020 N. Curson, Los Angeles, Calif.

Filed Oct. 13, 1961, Ser. No. 67,068

Term of patent 3½ years

(Cl. D86—10)

FIG. 1.

FIG. 2.

FIG. 3.

FIG. 1 is a front elevational view of a hair fluffer embodying my new design,

FIG. 2 is a side elevational view of the hair fluffer, and FIG. 3 is a rear elevational view thereof.

I claim:

The ornamental design for a hair fluffer, as shown.
